(57) CLAIM

I claim the ornamental design for a reclined bather, as shown and described.

DESCRIPTION

FIG. 1 is a top front perspective view of a reclined bather showing my new design
FIG. 2 is a top rear perspective view thereof;
FIG. 3 is a bottom rear perspective view thereof;
FIG. 4 is a front view thereof;
FIG. 5 is a rear view thereof;
FIG. 6 is a side view thereof, in a first configuration;
FIG. 7 is an adjacent side view thereof, in the first configuration thereof;
FIG. 8 is a top view thereof;
FIG. 9 is a bottom view thereof;
FIG. 10 is a side view thereof, in a second configuration; and,
FIG. 11 is a side view thereof, in a third configuration.
The broken lines in the drawing disclosure depict portions of the reclined bather that form no part of the claimed design.
